UNITED STATES PATENT OFFICE.

JOHN K. GRAHAM, OF WILMINGTON, DELAWARE.

TEMPLET.

No. 829,267.

Specification of Letters Patent.

Patented Aug. 21, 1906.

Application filed September 19, 1905. Serial No. 279,166.

To all whom it may concern.:

Be it known that I, JOHN K. GRAHAM, a citizen of the United States, residing in Wilmington, Delaware, have invented certain 5 Improvements in Templets, of which the following is a specification.

My invention relates to certain improvements in templets for marking out centers on bridge, ship, or structure metal-work, as set 10 forth in the application for patent filed by John D. Cummings, Serial No. 232,033, November 9, 1904, allowed May 29, 1905.

The object of my invention is to provide a templet for use in marking and punching the 15 centers of angle-beams, channel-bars, and other angular shapes. This object I attain in the following manner, reference being had to the accompanying drawings, in which—

Figure 1 is a perspective view of my improved templet shaped to be used in marking out the centers on angle-bars. Fig. 2 is a view showing my improved templet shaped to be used in marking out centers on channel bars or beams. Fig. 3 is a view illustrating 20 the method of applying the templet to a bar, and Fig. 4 is a view illustrating a templet applied to the bar and a center punch in position.

Referring in the first instance to Fig. 1, A is the templet, having two members *a a'*, one arranged at an angle to the other, preferably little less than a right angle, as shown at Fig. 3, so that when the templet is applied to the beam it can be forced into position, as shown 35 in Fig. 4, and will fit tightly against the two surfaces *b b* of the bar or beam B. The templet has holes *c* punched at intervals for the reception of the guiding-sleeve *e* of the punch E. This guiding-sleeve fits snugly in the 40 hole *c* and when in place, as shown in Fig. 4, acts as a support and guide for the plunger of the punch E, which has a small projection *e'* to form the center punch-hole in the bar or beam B. In making the templet A, I use 45 cardboard or binders' board of sufficient thickness that will give the templet rigidity. I then score it on the line *x*, so as to cut partly through the cardboard, and then bend it as shown in Fig. 1, after which, while the templet is held at the angle desired, staples *I* are secured to both parts *a a'* of the templet, as

illustrated in Figs. 1 and 3, the ends *i* of the staples which extend through the cardboard being clenched on the under side. When the staples are secured, the templet is of sufficient 55 rigidity to withstand the rough usage to which a templet in a bridge or structural iron shop is subjected. As before remarked, the templet is preferably shaped to a little less than a right angle, so that it can be forced 60 onto the right-angle beam or bar, as indicated in Figs. 3 and 4, but it may be made exactly at right angles in some instances, if desired.

In Fig. 2 I have shown a templet for use in marking out centers on channel-bars. In 65 this construction the templet is made with center section *A'* and side sections *a² a²*, each of these side sections, bent as described in Fig. 1, strengthened by a row of staples *I'*, as shown. Holes *c'* are punched in each end of 70 the section, in the present instance corresponding to the holes to be punched in the channel-beam. If other angular shapes are to be punched, the templet can be made accordingly. 75

I claim as my invention—

1. A templet for marking out centers in angle-work, consisting of a sheet of cardboard cut partially through at the bending-line and bent away from the cut so as to open 80 the same, to form two sections, one at an angle to the other, with a series of staples reinforcing the said angle-joint, the ends of the staples being embedded in the material so as to form a smooth inner surface in order that 85 the templet can be placed in close contact with the angle shape to which it is applied, substantially as described.

2. A templet for marking out centers in angle shapes, consisting of a sheet of cardboard cut partially through and bent away from the cut so as to open the same, to form two sections, said sections being bent at a little less than the angle of the bar or shape to which it is to be applied, so that on pressing the templet in position it will fit snugly upon the surface of the angle bar or shape, substantially as described. 95

3. A templet for marking centers in channel-bars, consisting of a body portion having 100 two side sections cut partially through at the lines of junction with said body portion and

bent away from the cuts so as to open the same, with a series of reinforcing-staples connecting the body portion with each of the side sections, the ends of the staples being
5 embedded in the material so that the templet will snugly fit the channel, substantially as described

In testimony whereof I have signed my name to this specification in the presence of two subscribing witnesses.

JOHN K. GRAHAM.
